WARDROBE TRUNK

Filed Sept. 2, 1927

3 Sheets-Sheet 2

The image contains two technical line drawings of a suitcase assembly, labeled Fig. 2.0 and Fig. 3.0.

Fig. 2.0: This drawing shows a top-down view of the suitcase's internal structure. It features a main compartment (10) with a horizontal divider (12). A hinged lid (8) is shown in an open position. A handle (15) is attached to the lid. A small pocket (105) is located on the side of the main compartment. The bottom of the suitcase is shown with a metal frame (19) and a series of rivets or bolts (11). A detailed view of the bottom right corner shows a metal plate (38) with a circular hole (1) and a small handle (39).

Fig. 3.0: This drawing shows a side view of the suitcase's bottom structure. It features a metal frame (11) with a series of rivets or bolts (16, 17). A small metal plate (25') is attached to the frame. A label (155) is present near the bottom left.

UNITED STATES PATENT OFFICE

JULIUS RITTER, JR., OF RACINE, WISCONSIN, ASSIGNOR TO HARTMANN TRUNK COMPANY, OF RACINE, WISCONSIN, A CORPORATION OF WISCONSIN

WARDROBE TRUNK

Application filed September 2, 1927. Serial No. 217,187.

This invention relates to improvements in wardrobe trunks.

Wardrobe trunks are usually divided vertically into two parts to form a wardrobe section and a drawer section. The two sections are hinged together to swing horizontally to open or closed position, and one of the sections is formed with an upper open end closed by a top cover. The wardrobe section 5 is provided with garment hangers for suspending outer wearing apparel thereon, and the other section is provided with drawers for holding other articles of wear.

Trunks of this type are often left in open 15 position in rooms, with the result that the garments in the wardrobe section are exposed to dust and surreptitious removal unless the sections are closed and locked.

It is one of the objects of the present invention to overcome the before mentioned objectionable feature, and provide a wardrobe trunk having inner top and front covers for the wardrobe section, which will protect the contents of said section.

25 A further object of the invention is to provide a wardrobe trunk having an inner front cover or door to which the inner top cover is hingedly connected.

A further object of the invention is to provide an inner hinged top cover having a pad or cushion for yielding engagement with the apparel draped over the garment hangers within the wardrobe section.

30 A further object of the invention is to provide a wardrobe trunk having novel means for locking the front cover or door in closed position by closing the inner top cover.

A further object of the invention is to provide a wardrobe trunk having a front cover 40 or door to which a shoe box is pivotally connected in a novel manner to permit the shoe box being swung upwardly to a more accessible position of use.

A further object of the invention is to provide a wardrobe trunk having a guard member 45 interposed between the front cover and the apparel draped and supported from the garment hangers, which automatically swings to closed position when the front door is swung to closed position.

A further object of the invention is to provide a wardrobe trunk which is of simple construction, is strong and durable, and is well adapted for the purpose described.

With the above and other objects in view, 55 the invention consists of the improved wardrobe trunk and its parts and combinations as set forth in the claims, and all equivalents thereof.

In the accompanying drawings in which the same reference characters indicate the same parts in all of the views:

Fig. 1 is a front view of the complete wardrobe trunk shown in open position;

Fig. 2 is a top view of the trunk shown in 65 open position;

Fig. 3 is a side detail view of the upper portion of the front door and the laundry bag mounted thereon;

Fig. 4 is a vertical sectional detail view of 70 the front door and the inner top door connected thereto;

Fig. 5 is a sectional detail view of the upper portion of the trunk showing the locking mechanism therefor;

Fig. 6 is a detail view of the shoe box in its lower position;

Fig. 7 is a similar view showing the shoe box in its upper position of use;

Fig. 8 is a fragmentary sectional view of 80 the shoe box in its lower position.

Referring to the drawings, the numeral 8 indicates the wardrobe section, and 9 the drawer section of a wardrobe trunk. The two sections are hinged together to swing 85 horizontally to open or closed position, and the wardrobe section is formed with an open top 8' which is closed by a top cover 11 hinged to the upper forward edge of the drawer section 9. Said cover swings forwardly over the open end of the wardrobe section when said section is in closed position.

The wardrobe section is provided with opposite side rails 10, garment hangers 10' slidably mounted thereon, and a garment retainer 12, while the other section 9 is provided with a plurality of slideable drawers 13 for holding other articles of wear. An inner front door or cover 14 connected to the inner

edge portion of the wardrobe section which is hinged to the drawer section 9 by hinges 15, is arranged to cover the front open portion of the wardrobe section. An inner top cover 16 connected to the upper edge portion of the front door 14 by a piano hinge 17 is adapted to extend over and cover the upper open end of the wardrobe section when the front door 14 is in closed position. When in open position, the top cover 16 may be swung outwardly and downwardly on the outer side of the front door 14, as shown in Fig. 2. The outer edge portion of the wardrobe section 8 is provided with a vertically extending frame member 18 having elongated slots 19 formed therein, which are adapted to receive hook-shaped bolts 20 mounted on the reciprocable locking bar 21. Said bar 21 is reciprocally connected to the front door, and at its upper end is pivotally connected to the top cover 16 by a link 22, so that when the front door is closed and the top cover is swung to closed position, the bolts 20 will be moved downwardly into locking engagement with the slotted portions 19 of the frame member 18. The frame member is also provided with a lower elongated slot 19' which receives the guide bolt 20' when the front door 14 is swung to closed position to align the door vertically with the trunk section and to prevent surreptitiously disengaging the bolts from the slotted portions of the frame.

The inner top cover 16 of the wardrobe section is provided with a keyed locking member 23 adjacent its hinged edge having an elongated bolt 24 which extends through the cover to the opposite edge and is adapted to lockingly engage the escutcheon plate 26 secured to the rear upper edge portion of the wardrobe section, as shown in Figs. 2 and 5. The locking member, when the cover is in closed position, extends through an opening 25' to permit the use of a key (not shown). To unlock the top cover, the key is turned to unlocked position, and the bolt lever 26 is then pulled upwardly to release the bolt from the escutcheon plate 25. The top cover 16 is provided with stop members 27 mounted on its inner hinged edge portion which engage one side portion of the front door when the cover is in closed position to limit the down swing of said cover when in cushioning position, as indicated by dotted lines in Fig. 4. The wardrobe section is also provided with a guard member in the form of a door member 28 which is hinged to the inner side of the wardrobe section 8 adjacent the trunk section hinges and engaged by the inner side of the shoe box 29 and moved to closed position thereby. Said door member 28 serves as a guard to prevent apparel supported from the garment hangers 10' from entering the space between the hinged side of the shoe box and one side of the wardrobe section. A

cushion 30 is mounted on the lower side of the inner top cover, and is adapted to engage the garment hangers 10' and the garments draped thereon, when the top cover is swung to closed position. When in said closed position, the upper portions of the hangers and the garments will imbed into the cushion, and will be held in position by the cushion without injury to garments. 70

The shoe box 29 is connected to the inner side of the front door 14 by pairs of upper and lower links 31 and 32, which normally hold the box in its closed lower position against the inner side portion of the door, as shown in Figs. 1 and 6. To open the box, it is only necessary to pull upwardly on the handle 33 to swing the box upwardly and horizontally to the convenient position shown in Fig. 7 to permit the opening of the cover 29'. The links 31 and 32 are so connected to the parts that when the box is swung upwardly and outwardly, the box will be automatically held in its upper position of accessibility. 75

A laundry bag 34 removably connected to the inner side of the front door 14 above the shoe box 29 by snap buttons 35, is provided for holding soiled garments, and is removable to permit cleaning. 80

The locking of the two sections together is controlled by the trunk top cover 11 engaging the lock member 37. The top cover 11 is provided with a hasp lock 38 for locking said top cover to the wardrobe section 8. The outer top cover 11 also carries a cushion or pad 39 which bears down on the inner top cover 16 to yieldingly reinforce said inner top cover. 85

From the foregoing description, it will be seen that the wardrobe trunk is of very simple construction and is well adapted for the purpose described. 90

What I claim as my invention is:

1. The combination with a wardrobe trunk formed of two hinged together sections swingable horizontally to open position, one of said sections having an open top and an open front closed by the other section, an outer top cover hinged to one of the sections for closing the upper open end of the other section, an inner front door interposed between the two sections and hingedly connected to one of the sections for closing the open front, an inner top cover hinged to the upper edge portion of the front door for closing the upper open top and swingable to an open position alongside of the front door, garment hangers within the section with the open top guard means within the wardrobe section controlled by the movement of the front door, a cushion mounted on the lower side of the inner top cover for engaging the garment hangers or the garments draped thereon when the cover is in closed position, and a cushion mounted on the lower side of 100

the outer top cover for yieldingly engaging and holding said inner top cover in its garment engaging position when both covers are in closed position, said inner front door and 5 inner top cover permitting closing the open top section while the two sections remain in open position.

2. The combination with a wardrobe trunk formed of a wardrobe section and a drawer 10 section hinged together and swingable horizontally to open position, the wardrobe section having an open top and an open front closed by the drawer section, an outer top cover hinged to the forward edge of the 15 drawer section for closing the upper open end of the wardrobe section, garment hangers within the upper portion of the wardrobe section, a front door hinged to one of the sections for closing the open front of the wardrobe section, an inner top cover hinged to the upper edge portion of the front door for closing the upper open top of the 20 wardrobe section, said cover being swingable to open position alongside of the front door, a guard door within the wardrobe section movable to closed position by the closing movement of the inner front door, spacing 25 means mounted on the lower side of the inner top cover for engaging the garment hangers or the garments draped thereon when the cover is in closed position, and spacing means mounted on the lower side of the outer top 30 cover for engaging the inner top cover when both covers are in closed position.

3. The combination with a wardrobe trunk formed of a wardrobe section and a drawer section hinged together and swingable horizontally to open position, the wardrobe section having an open top and an open front 40 closed by the drawer section, an outer top cover hinged to the forward edge of the drawer section for closing the upper open end of the wardrobe section, garment hangers within the upper portion of the wardrobe 45 section, an inner front door hinged to one of the sections for closing the open front of the wardrobe section, an inner top cover hinged to the upper edge portion of the front door for closing the upper open top 50 of the wardrobe section and swingable to an open position alongside of the front door, a shoe box pivotally connected to the lower inner side portion of the front door and movable to an upper position of accessibility when 55 the front door is in open position, a guard door within the wardrobe section moved to closed position by the closing movement of the inner front door, a cushion mounted on the lower side of the inner top cover for engaging the garment hangers or the garments draped thereon when the cover is in closed position, and a cushion mounted on the lower side of the outer top cover for yieldingly engaging the inner top cover when both covers 60 65 are in closed position.

4. The combination with a wardrobe trunk formed with a wardrobe section and a drawer section hinged together and swingable horizontally to open position, the wardrobe section having an open top and an open front 70 adapted to be closed by the drawer section, an outer top cover hinged to the forward edge of the drawer section for closing the upper open end of the wardrobe section, garment hangers within the upper portion of the 75 wardrobe section, a front door hinged to one of the sections for closing the open front of the wardrobe section, an inner top cover hinged to the upper edge portion of the front door for closing the upper open top of the 80 wardrobe section, said cover being swingable to open position alongside of the front door, a guard door within the wardrobe section movable to closed position by the closing movement of the inner front door, spacing 85 means mounted on the lower side of the inner top cover for engaging the garment hangers or the garments draped thereon when the cover is in closed position, and spacing means mounted on the lower side of the outer top 90 cover for engaging the inner top cover when both covers are in closed position.

In testimony whereof, I affix my signature.
